HYDRAULIC DRIVE FOR WINDING MACHINES

Ransom Tyler, Greenfield, and Ewald H. Parduhn,
Milwaukee, Wis., assignors to The Oilgear Company,
Milwaukee, Wis., a corporation of Wisconsin

Application June 12, 1948, Serial No. 32,578

20 Claims. (Cl. 242—75)

1

This invention relates to hydraulic drives for winding machines and more particularly to a winder drive of the type employed to drive a winding shaft upon which a sheet, strip or strand of flexible material is wound into a roll as fast as the material is delivered thereto from another machine or from another part of the machine of which the winding shaft forms a part.

A winder drive must maintain tension on the material during the winding operation and the tension must be maintained within close limits in order to produce a roll of the desired density and to prevent the material from wrinkling, buckling or breaking or the inner turns of the material from moving axially during the winding of other turns outward therefrom.

The present invention has as an object to provide a winder drive capable of maintaining the correct tension upon flexible material while winding the material into a roll which has a very large outside diameter relative to the diameter of the core upon which the material is wound.

Another object is to provide a winder drive in which the tension on the material being wound into a roll may be maintained constant or may be varied at a predetermined rate throughout the winding operation.

Another object is to provide a hydraulic winder drive which will maintain the correct tension upon the material without wasting power or heating the motive liquid by directing a part of the motive liquid through a resistance as is customary in some of the prior drives.

Another object is to provide a winder drive which after completing one roll may quickly and easily be reset to wind another roll.

Another object is to provide a winder drive which will maintain a substantially constant tension upon the material being wound into a roll until the roll is of substantial diameter and thereafter to maintain a gradually decreasing tension upon the material.

Other objects and advantages will be apparent from the description hereinafter given of a winder drive in which the invention is embodied.

The invention is exemplified by the winder drive shown schematically in the accompanying drawings in which the views are as follows:

Fig. 1 is a diagrammatic view illustrating the hydraulic circuit of an embodiment of the invention and showing the relation of the various parts to each other.

Figs. 2 and 3 are views showing a directional control valve in positions different from those shown in Fig. 1.

2

Figs. 4 and 5 are views showing another valve in positions different from those shown in Fig. 1.

Fig. 6 is a diagram of an electric circuit which may be employed to control the drive shown in Fig. 1.

Fig. 7 is a diagrammatic representation of the relays indicated in Fig. 6.

For the purpose of illustration, the drive has been shown as being employed to drive the shaft 1 of a winding machine and cause it to wind a strip of paper 2 thereon into a roll 3 as fast as the paper is delivered by the delivery rolls 4 of a calender. Since the winding machine, the calender and the paper do not per se form any part of the present invention, only parts thereof have been indicated in the drawing.

The drive includes a hydraulic transmission for driving the winding machine and a control for starting and stopping the transmission and for causing the drive to maintain a substantially constant tension upon the paper as it is wound into a roll.

The transmission includes a rotary hydraulic motor 5 which is adapted to drive shaft 1 through a suitable drive 6, a pump 7 which is continuously driven when the drive is in operation and which is adapted to deliver motive liquid to motor 5 to energize it, and a control valve 8 which controls the delivery of liquid from pump 7 to motor 5 and which is connected to pump 7 by two channels 9 and 10 and to motor 5 by two channels 11 and 12.

Channel 9 has been shown connected to a pressure switch 13 which forms a part of the electric circuit shown in Fig. 6 and which closes in response to pump 7 creating sufficient pressure to enable motor 5 to drive shaft 1 and enable it to exert a given pull upon paper 2. Pressure switch 13 will open and break the electric circuit in response to paper 2 breaking as will presently be explained. Channel 12 has connected therein a check valve 14 which permits liquid to flow freely therethrough from motor 5 to valve 8 but prevents liquid from flowing through channel 12 from valve 8 to motor 5. Channel 12 also communicates with the inlet of a resistance valve 15 which will hereinafter be referred to as a brake valve for the reason that it resists the discharge of liquid from motor 5 and thereby imposes a brake load thereon when the drive is being stopped. Valve 15 has its outlet connected by a channel 16 to a reservoir 17 from which pump 7 is supplied with liquid.

Control valve 8 has an axial bore 20 formed in its casing 21 and a valve member 22 slidably

fitted in bore 20 to control communication between five annular grooves or ports 23, 24, 25, 26 and 27 which are formed in the wall of bore 20. Channel 9 communicates with port 23 which is arranged intermediate the ends of bore 20. Channels 11 and 12 communicate, respectively, with ports 24 and 25 which are arranged at opposite sides of port 23. Channel 10 has several branches and communicates with ports 26 and 27 which are arranged outward from ports 24 and 25 respectively. Channel 10 also communicates with bore 20 at points adjacent both ends thereof so that movement of valve member 22 may not be hampered by liquid trapped in the end portions of bore 20.

Valve member 22 is urged to and normally held in its central or neutral position by two springs 28 and 29, which are arranged in opposite end portions of bore 20, and it is adapted to be moved in one direction or the other by one or the other of two solenoids 30 and 31 which have been shown as having the armatures thereon connected directly to the stems of valve member 22 but in practice valve member 22 is shifted in opposite directions selectively by two hydraulic servomotors controlled by separate pilot valves which are shifted by solenoids corresponding to solenoids 30 and 31.

The arrangement is such that, when valve member 22 is in the position shown in Fig. 1, port 23 is open to ports 24 and 26 and port 25 is blocked so that pump 7 is bypassed through valve 8 and, if motor 5 is being driven by roll 3, it will be supplied with liquid from valve 8 and it will have to discharge through brake valve 15 which will quickly decelerate it to zero speed.

When valve member 22 is in the position shown in Fig. 2, liquid discharged by pump 7 will flow through channel 9, valve 8, channel 11, motor 5, channel 12, valve 8 and channel 10 to the intake of pump 7, thereby energizing motor 5 which will drive shaft 1. When valve member 22 is in the position shown in Fig. 3, the liquid discharged by pump 7 will flow through channel 9 and valve 8 into channel 12 and be employed for resetting the control as will presently be explained. The liquid cannot flow through channel 12 to motor 5 due to check valve 14.

Pump 7, which is continuously driven when the drive is in operation, is of the type which will discharge liquid at a predetermined maximum rate until pump pressure reaches a predetermined maximum and then it will automatically reduce its displacement until it is discharging just enough liquid to maintain that maximum pressure constant, such as the pump shown in Patent No. 2,080,810.

Since such pumps are well known and in extensive commercial use, it is deemed sufficient to state herein that pump 7 is provided with a control 35 which reduces pump displacement in response to pump pressure reaching a given maximum and that control 35 is adjustable to vary the pressure at which it will operate.

Control 35 has been shown as being adjustable by means of a shaft 36 which has been indicated as being a screw for varying the tension of a spring (not shown) which determines the pressure at which the control will operate as such an arrangement is according to the usual practice but the control may be adjusted by other means as it is only necessary that the adjusting element, such as shaft 36, be rotary in order that it may be operated in response to roll 3 increasing in diameter as will presently be explained.

Shaft 36 is connected by suitable gearing such as gears 37 and 38 to the screw 39 of a limit switch 40 which limits the adjustment of control 35, as will presently be explained, and which has been shown in Fig. 6 as including two alternatively operable switches LS1 and LS2. Shaft 36 is also connected by suitable gearing such as two gears 41 and 42 to an adjusting shaft 43 which is connected through an overrunning clutch 44 and a reduction gear 45 to a small pilot motor 46. Reduction gear 45 is also connected through an overrunning clutch 47 to a reset shaft 48 which is connected to adjusting shaft 43 by a suitable drive 49.

15 Pilot motor 46 is adapted to adjust control 35 in response to roll 3 increasing in diameter. As shown, motor 46 is energized by liquid delivered thereto in response to variations in the volumetric delivery of a small variable displacement pilot pump 55 relative to the volumetric delivery of a small variable displacement pilot pump 56. Pump 55 is driven at a speed proportional to the linear speed of paper 2 as by being connected to calender rolls 4 by a suitable drive 51. Pump 56 is driven at a speed proportional to the rotary speed of roll 3 as by being connected to the shaft of motor 5 by a suitable drive 53.

20 Pilot pumps 55 and 56 are connected in series by two channels 59 and 60 which form therewith a hydraulic pilot circuit of the "closed" type. That is, all of the liquid discharged by either pump enters or attempts to enter the other pump. Channel 59 is connected intermediate its ends by a channel 61 to the normal outlet of pilot pump 46 and channel 60 is connected intermediate its ends by a channel 62 to a reversing valve 63 which is connected by a channel 64 to the normal inlet of motor 46.

25 The pressures created by pumps 55 and 56 are limited, respectively, by two relief valves 65 and 66 which have been shown connected between channels 59 and 60 but which in practice are arranged inside the pump casings as is customary.

30 Valve 63 includes a valve casing 70 having an axial bore 71 formed therein and a valve member 72 slidably fitted in bore 71 to control communication between four annular grooves or ports 73, 74, 75 and 76 which are formed in the wall of bore 71. Ports 73 and 74 have channels 62 and 64 connected thereto respectively. Ports 75 and 76 and the end portions of bore 71 communicate with branches of an exhaust channel 77 which discharges into reservoir 17.

35 Valve member 72 is urged to and normally held in its central or neutral position by two springs 78 and 79, which are arranged in opposite end portions of bore 71, and it is adapted to be moved in one direction or the other by one or the other of two solenoids 80 and 81 which have been shown 40 as having the armatures thereof connected directly to the stems of valve member 72 but in practice valve member 72 is shifted in opposite directions selectively by two hydraulic servomotors controlled by separate pilot valves which 45 are shifted by solenoids corresponding to solenoids 80 and 81.

40 The arrangement is such that, when valve member 72 is in its central or neutral position as shown in Fig. 1, port 73 is open to exhaust channel 77 and port 74 is blocked so that if pump 55 is driven by roll 4, it can discharge into reservoir 17 and pump 56 cannot be operated by liquid discharged by pump 55.

45 When valve member 72 is in the position shown 50 in Fig. 4, channels 62 and 64 are in commun-

5

cation with each other so that, when pump 55 discharges liquid in excess of the liquid which can enter pump 56, the excess liquid will flow to motor 46 and cause it to adjust the control.

When valve member 72 is in the position shown in Fig. 5, port 74 is open to exhaust channel 77 and port 73 is blocked so that motor 46 may be reversed to reset the controls.

Reversal of motor 46 is effected by supplying liquid to channel 64 from pump 7. As shown, channel 59 is connected by a channel 82 to channel 12 at a point between valve 8 and check valve 14 so that, when valve member 22 is shifted to the position shown in Fig. 3, liquid may flow from pump 7 through channel 9, valve 8, channels 12, 82, 59 and 64 to motor 46 and cause it to operate in the reverse direction and to discharge liquid through channel 64, valve 63 and channel 77 into reservoir 17. Channel 82 has connected therein a flow control valve 83, which limits the rate at which liquid may flow from pump 7 to motor 46, and a check valve 84 which permits liquid to flow from channel 12 to channel 59 but prevents the flow from channel 59 to channel 12.

The pilot circuit is kept flooded with liquid by a gear pump 85 which in practice is driven in unison with pump 7 and is arranged in the casing thereof as is customary but which for the purpose of illustration has been shown separate from pump 7. Gear pump 85 draws liquid from reservoir 17 and discharges it into a channel 86 which is connected to the return side of the pilot circuit as by being connected to channel 82 through a check valve 87 which permits gear pump 85 to supply liquid to the pilot circuit but prevents flow from the pilot circuit into the gear pump circuit.

Liquid discharged by gear pump 85 ordinarily is also used for control purposes and may be used to supercharge pump 7 when motor 5 is driving shaft 1 but such use has not been illustrated as it is according to common practice. Gear pump 85 discharges liquid at a rate in excess of requirements and the excess liquid is exhausted into reservoir 17 through a low pressure relief valve 88 which enables gear pump 85 to maintain a low pressure in the return side of the pilot circuit.

Pump 55 is a well known type which has its displacement varied by means of a screw 95 having an adjusting knob 96 fixed to the outer end thereof so that pump displacement may be adjusted manually. Pump 56 is the same type as pump 55 and it has its adjusting screw 97 connected by a suitable drive 98 to adjusting shaft 43 so that the displacement of pump 56 is adjusted when shaft 43 rotates.

Pumps 55 and 56 are initially so adjusted that each will discharge liquid at exactly the same volumetric rate each time shaft 1 first starts to wind paper thereon, that is, when the paper has been attached to a suitable core on shaft 1 and shaft 1 has rotated just enough to pull the slack out of the strip of paper between it and the calender.

Rotation of shaft 1 will cause paper to accumulate thereon and form a roll 3 which will gradually increase in diameter. Since the peripheral speed of roll 3 remains equal to the linear speed of paper 2, the rotary speed of shaft 1 will decrease relative to the linear speed of paper 2 in proportion to the increase in the diameter of roll 3, thereby causing pump 56 to slow down so that all of the liquid discharged by pump 55 cannot enter pump 56. The liquid discharged

6

by pump 55 in excess of the liquid which can enter pump 56 will flow from channel 60 through channel 62, valve 63, channel 64, motor 46 and channel 61 into return channel 59 and cause motor 46 to rotate adjusting shaft 43 through reduction gear 45 and clutch 44.

Reduction gear 45 will also tend to rotate reset shaft 48 but overrunning clutch 47 will prevent motion from being transmitted from reduction gear 45 to shaft 48 and will permit shaft 48 to be rotated idly by shaft 43 through drive 49.

Rotation of shaft 43 causes drive 98 to turn adjusting screw 97 to increase the displacement of pump 56. Since pump 55 is driven at a speed proportional to the linear speed of paper 2 and pump 56 is driven at a speed proportional to the rotary speed of shaft 1 which gradually decreases relative to the speed of paper 2 as roll 3 increases in diameter, and since motor 46 is energized solely by liquid discharged by pump 55 in excess of the liquid which can enter pump 56, the displacement of pump 56 will be increased at a rate proportional to the rate at which roll 3 increases in diameter, thereby causing the speed of shaft 43 to be maintained at a rate proportional to the rate at which roll 3 increases in diameter.

Motor 5 can wind paper 2 onto shaft 1 only as fast as paper 2 is delivered by rolls 4, and 30 it must exert sufficient torque to maintain a given tension on paper 2 in order to produce a roll 3 of the desired density. Pump control 35 is initially so adjusted that, as soon as motor 5 has exerted the desired tension upon paper 2, 35 it will cause pump 7 to reduce its displacement until it is delivering just enough liquid to enable motor 5 to wind up paper 2 as fast as it is delivered by roll 4 and to maintain the desired tension on paper 2.

40 As roll 3 gradually increases in diameter, motor 5 must drive shaft 1 at a gradually decreasing speed and it must exert a gradually increasing torque in order to maintain the desired tension upon paper 2, thereby requiring pump 7 to gradually decrease its displacement and to gradually increase the pressure of the liquid delivered to motor 5.

However, gradual rotation of adjusting shaft 43 causes gears 42 and 41 to gradually turn shaft 36 which will adjust control 35 to require a gradually increasing pressure to enable it to reduce the displacement of pump 7, thereby causing pump 7 to deliver liquid to motor 5 at a gradually decreasing rate and at a gradually increasing pressure. Since shaft 43 is rotated at a speed proportional to the rate at which roll 3 increases in diameter as explained above, the reduction in pump displacement and the increase in pump pressure will be proportional to the rate at which roll 3 increases in diameter. Consequently, the torque of motor 5 will increase at the rate at which roll 3 increases in diameter so that motor 5 will maintain a constant tension on paper 2.

65 The drive may be controlled manually such as by shifting the valves manually or shifting the valves as by means of the solenoids controlled by individual manually operated switches but preferably the drive is controlled by an electric circuit such as that shown in Fig. 6.

As shown, solenoid 30 is controlled by a relay R1, solenoid 80 is controlled by a relay R2 and a relay R3, solenoids 31 and 81 are controlled by a relay R4, relay R1 is controlled by relay R2 and a starting switch S1, relay R2 is con-

trolled by pressure switch 13, relay R3 is controlled by limit switch 40, relay R4 is controlled by limit switch 40 and by a reset switch S2, and all four relays are under the control of a stop switch S3.

Electric current for energizing the solenoids and the magnets of the relays is supplied thereto from two power lines L1 and L2 which are connected to opposite sides of an electric power circuit through a suitable switch not shown.

The winding of solenoid 30 is connected to line L1 by a wire 109 and it is connectable to line L2 through a wire 101, relay contact R1^a and a wire 102. The winding of solenoid 80 is connected to line L1 by a wire 103 and it is connectable to line L2 through a wire 104, relay contact R2^b, a wire 105, relay contact R3^c and a wire 106. The magnet R1^a of relay R1 is connected to line L1 and it is connectable to line L2 through a wire 107, starting switch S1 and a wire 108 and it is also connectable to line L2 through a wire 109, relay contact R1^b, a wire 110, relay contact R2^c, a wire 111, stop switch S3 and a wire 112.

The winding of solenoid 31 is connected to line L1 by a wire 113 and it is connectable to line L2 through a wire 114, relay contact R4^c, a wire 115, wire 111, stop switch S3 and wire 112. The winding of solenoid 81 is connected to line L1 by a wire 116 and it is connected to wire 114 by a wire 117 so that solenoids 31 and 81 are operated in unison.

The magnet R2^a of relay R2 is connected to line L1 and it is connectable to wire 115 through a wire 118, pressure switch 13 and a wire 119. The magnet R3^a of relay R3 is connected to line L1 and it is connectable to wire 115 through a wire 120, switch LS2 of limit switch 40 and a wire 121 and also through a wire 122, relay contact R3^b and a wire 123. The magnet R4^a of relay R4 is connected to line L1 and it is connectable to wire 115 through a wire 124, reset switch S2 and a wire 125 and also through a wire 126, relay contact R4^b and a wire 127, switch LS1 of limit switch 40, and a wire 128.

It is desirable that the operator be notified when pump control 35 has been adjusted to a predetermined limit. This may be accomplished by causing relay R3 to effect operation of a signal such as a lamp 129. As shown, a transformer 130 has the ends of its primary winding connected to lines L1 and L2 by two wires 131 and 132 and one end of its secondary winding connectable to the other end thereof through a wire 133, relay contact R3^d, a wire 134, lamp 129 and a wire 135 so that lamp 129 will be lighted when relay R3 is operated.

Operation

Assuming that main pump 7 and gear pump 35 are running, that the end of the strip of paper 2 has been fastened to a suitable core fixed on winding shaft 1, that pilot pumps 55 and 56 have been so adjusted that they will discharge liquid at the same volumetric rate when the drive is started and that pump control 35 has been so adjusted that pump 7 will create just enough pressure to enable motor 5 to exert just enough torque to exert the proper tension upon paper 2 when the drive is started, the drive will operate as follows:

With the parts in the positions shown in Fig. 1 pump 7 will be at full stroke and will circulate liquid idly through valve 8, and gear pump 35 will discharge through relief valve 88 and will

7 maintain a low pressure in the pilot circuit but that pressure cannot cause pilot motor 46 to operate because channel 64 is blocked at valve 63.

The drive may be started by closing starting switch S1 which will establish a circuit (L1—R1^a—107—S1—108—L2) to cause relay R1 to close and establish a circuit

(L1—100—101—R1^a—102—L2)

10 to energize solenoid 30 which will shift valve member 22 of valve 8 to the position shown in Fig. 2. Then all of the liquid discharged by pump 1 will flow through channel 9, valve 8 and channel 11 to motor 5 and cause it to rotate shaft 1 and the liquid discharged by motor 5 will flow through channel 12, valve 8 and channel 10 to the intake of pump 7.

15 Since at this time the load on motor 5 is very light and pump 7 is at full stroke, motor 5 would accelerate very rapidly if switch S1 were held closed and, if there were considerable slack in the strip of paper 2 between shaft 1 and rolls 4, motor 5 would gain so much momentum before the slack was pulled out that the strip would be broken when it became taut. Therefore, motor 25 5 should be "inched" until all slack is pulled out of the paper. That is, switch S1 should be closed and opened repeatedly and held closed only momentarily so that motor 5 cannot accelerate to a speed high enough to cause the paper to break when it becomes taut. If the paper is pulled taut before being fastened to the core on shaft 1, inching would be unnecessary.

20 Pilot pump 56 will be driven a limited amount by motor 5 during the inching process but the liquid discharged by pump 56 cannot cause pilot motor 46 to rotate as channel 64 is blocked at valve 63. The limited amount of liquid discharged by pump 56 at this time is bypassed 30 through relief valve 66 to the intake of pump 56.

25 Until the paper becomes taut, relay R1 will open and deenergize solenoid 30 to permit valve member 22 to return to neutral each time starting switch S1 opens because a holding circuit for relay R1 cannot be established until pressure switch 13 closes. However, when switch S1 is closed after the paper becomes taut, a circuit will be established through magnet R1^a and solenoid 30, valve member 22 will be shifted to direct liquid from pump 7 to motor 5, as explained above, and motor 5 will try to wind paper 2 upon shaft 1 which will cause pump pressure to rise. When pump pressure reaches a given value, pressure switch 13 will close and establish a circuit

35 (L1—R2^a—118—13—119—115—111—S3—112—L2)

40 to cause relay R2 to close and establish a circuit

(L1—R1^a—109—R1^b—110—R2^c—111—S3—112—L2)

45 to hold relay R1 closed when starting switch S1 is released, thereby maintaining the previously established circuit through solenoid 30 which will hold valve member 22 in the position shown in Fig. 2.

50 Relay R2 will also establish a circuit

(L1—103—80—104—R2^b—105—R3^c—106—L2)

55 to energize solenoid 80 which will shift valve member 72 of valve 63 to the position shown in Fig. 4.

60 When pump pressure reaches the value necessary to enable motor 5 to exert the desired tension upon paper 2, control 35 will reduce the dis-

placement of pump 7 until pump 7 is delivering just enough liquid to maintain its pressure at that value.

Then when the calender is started, motor 5 will start to rotate shaft 1 and control 35 will automatically increase the displacement of pump 7 until pump 7 is delivering liquid at the rate required to enable motor 5 to wind paper 2 upon shaft 1 into a roll 3 as fast as the paper is delivered by rolls 4.

Pilot pump 55 will be driven by rolls 4 at a speed proportional to the linear speed of paper 2 and pilot pump 56 will be driven by motor 5 at a speed proportional to the rotary speed of shaft 1 and the two pilot pumps will at first discharge liquid at the same rate but, as the paper accumulates upon shaft 1, pump 56 will slow down due to the increase in the diameter of the roll 3 of paper upon shaft 1. Therefore, pump 55 will discharge liquid in excess of the liquid which can enter pump 56 and the excess liquid will flow through motor 46 and cause it to adjust the control 35 of pump 7 and the control 97 of pump 55 at a rate proportional to the rate at which roll 3 increases in diameter, as previously explained, so that pump 7 delivers liquid to motor 5 at a pressure which increases at the rate necessary to enable motor 5 to maintain a constant tension upon paper 2 while winding it into a roll 3 as fast as the paper is delivered by rolls 4.

The drive may continue to operate in the above manner until control 35 has been adjusted to its maximum pressure limit at which time roll 3 will be very much larger in diameter relative to the diameter of its core than any roll which can be produced with the prior winder drives.

If the material to be wound into a roll is of a type which should not be wound under a constant tension but should be wound under a gradually decreasing or a gradually increasing tension, it is only necessary to change the speed ratio between adjusting shaft 43 and pump adjusting element 36.

Limit switch 40 is operated in unison with the adjustment of pump control 35 and, immediately after adjustment of control 35 begins, switch LS1 of limit switch 40 will close but it will have no effect at that time as the circuit therethrough is open at switch R4^b of relay R4.

When control 35 has been adjusted to its maximum pressure limit, switch LS2 of limit switch 40 will close and establish a circuit (L1—R3^a—120—LS2—121—115—111—S3—112—L2) to energize magnet R3^a which will cause relay R3 to operate and establish a circuit (L1—R3^a—122—R3^b—123—115—111—S3—112—L2) to keep magnet R3^a energized when switch LS2 opens.

Operation of relay R3 causes the contact R3^c thereof to open and break the circuit through solenoid 80 which is thus deenergized to permit spring 78 to shift valve member 72 of valve 63 to its central position so that continued operation of pilot pump 55 cannot cause further adjustment of pump control 35.

Operation of relay R3 also causes the contact R3^d thereof to close the circuit through the secondary winding of transformer 139 which will cause signal 129 to operate and notify the operator that pump control 35 has been adjusted to its maximum pressure limit.

The operator may then stop the drive by opening stop switch S3 or, if a larger roll of paper is desired, he may permit the drive to continue to operate in which case control 35 will cause pump 7 to continue to deliver liquid at the predeter-

mined maximum pressure and to gradually decrease its displacement as roll 3 increases in diameter but the tension exerted on paper 2 will gradually decrease as roll 3 increases in diameter because pump pressure remains constant.

If rolls 4 should be stopped, motor 5 would try to continue to wind up paper 2 but it could not do so as the paper would be held stationary by rolls 4. Therefore, motor 5 would stop and control 35 would immediately effect adjustment of pump 7 until it was delivering just enough liquid to make up for leakage losses and to enable motor 5 to maintain the desired tension upon paper 2. Then when rolls 4 were started, control 35 would immediately effect adjustment of pump 7 until it was delivering enough liquid to enable motor 5 to wind up paper 2 as fast as it was delivered by rolls 4 and to maintain the desired tension upon paper 2.

The drive is thus capable of maintaining the correct tension upon the material regardless of whether the material is moving or is stationary and regardless of the size of the roll of material up to the maximum diameter determined by the maximum pressure limit of the control 35.

The drive may be stopped at any time by opening stop switch S3 which will break the circuits through the magnets of all of the relays which had been operated and it will be stopped automatically if the paper should break at any time.

If the paper should break, the load would be removed from motor 5 which would cause pump pressure to drop and permit pressure switch 43 to open and break the circuit through the magnet R2^a of relay R2 and permit switches R2^b and R2^c to open. Switch R2^b would break the circuit through solenoid 80 which would be deenergized and permit valve member 72 of valve 63 to return to its neutral position. Switch R2^c would break the circuit through magnet R1^a of relay R1 and permit switches R1^b and R1^c to open. Switch R1^b would open another gap in the holding circuit of magnet R1^a. Switch R1^c would break the circuit through solenoid 30 which would be deenergized and permit valve member 22 of valve 8 to return to its neutral position so that pump 7 would be bypassed through valve 8 and the liquid discharged by motor 5 would be exhausted through brake valve 15 which would decelerate motor 5 and quickly bring it to a stop as previously explained.

After roll 3 reaches the desired diameter, the drive is stopped as explained above, the roll removed from shaft 1 and the controls reset in preparation for winding another roll of paper upon shaft 1.

The controls are reset by closing reset switch S2 which establishes a circuit (L1—R4^a—124—S2—125—115—111—S3—112—L2) to energize magnet R4^a which will close switches R4^b and R4^c. Switch R4^b will establish a circuit (L1—R4^a—126—R4^b—127—LS1—128—115—111—S3—112—L2) to keep magnet R4^a energized when switch S2 is released. Switch R4^c will establish a circuit (L1—113—31—114—R4^c—115—111—S3—112—L2) to energize solenoid 31. Since solenoid 31 is connected in parallel with solenoid 81 by wires 116 and 117, it will be energized also.

Solenoid 31 will shaft valve member 22 of valve 8 to the position shown in Fig. 3 and solenoid 81 will shaft valve member 72 of valve 63 to the position shown in Fig. 5. Then pump 7, which went to full stroke when valve member 22 was previously shifted to its neutral position, will

deliver liquid through channel 9, valve 8, channels 12, 82, 59 and 61 to pilot motor 46 which will be operated in a direction opposite to that in which it operated when adjusting the controls and it will discharge liquid through channel 64, 5 valve 63 and channel 77 into reservoir 17.

The displacement of motor 46 is only a small fraction of the full displacement of pump 7 and, if motor 46 were operated by the full volumetric delivery of pump 7, it would be driven at such a 10 high speed that it would soon be destroyed. However, flow control valve 83 limits the flow to motor 46 to a rate which will cause motor 46 to operate at a safe high speed and the resistance of valve 83 causes pump pressure to rise sufficiently to enable control 35 to adjust pump 7 until it is delivering liquid at the rate determined by valve 83.

Motor 46 will drive reset shafts 48 at high speed through overrunning clutch 47 but it cannot drive adjusting shaft 43 due to overrunning clutch 44. Shaft 48 will rotate shaft 43 through drive 49 at high speed in the reverse direction, that is, in a direction opposite to that in which it rotates when adjusting pump controls 35 and 91. Screw 36 will be rotated in the reverse direction by shaft 43 through gears 42 and 41, screw 39 of limit switch 40 will be rotated in the reverse direction by screw 36 through gears 37 and 38, and pump adjusting member 97 of pump 56 will be rotated in the reverse direction by shaft 43 through drive 98 at such high speeds that the controls will be reset in a very short time such as four or five seconds.

When the controls are adjusted to their initial positions, switch LS1 of limit switch 40 will open and deenergize the magnet R4^a of relay R4 which will cause switches R4^b and R4^c to open. Switch R4^b will provide a second gap in the holding circuit of relay R4 so that it cannot be reestablished until both of switches R4^b and LS1 are closed. Switch R4^c will break the circuit through solenoids 31 and 81 which will thus be deenergized and permit valve members 22 and 72 to return to their neutral positions so that pump 7 will be bypassed and the drive brought to rest with the parts thereof in positions to start another cycle of operations when starting switch S1 is closed as explained above.

The winder drive illustrated and described herein may be modified in various ways without departing from the scope of the invention which is hereby claimed as follows:

1. In a hydraulic drive for rotating a winding shaft on which flexible material is wound into a roll as fast as said material is delivered by a machine, the combination of a main hydraulic motor connected to said shaft to rotate the same, a main pump for supplying motive liquid to said motor to enable it to drive said shaft, said main pump having a control which in response to the pressure created by said pump rising to a given value will automatically reduce the displacement of said pump until said pump is delivering just enough liquid to maintain the pump pressure at that value and which includes an element for adjusting said control to vary the pressure required to effect operation of said control, a first pilot pump driven at a speed proportional to the linear speed of said material, a second pilot pump driven at a speed proportional to the rotary speed of said roll of material so that the speed of said second pilot pump decreases relative to the speed of said first pilot pump as said roll increases in diameter, said second pilot pump having a

member rotatable to vary its displacement, a hydraulic pilot motor adapted to be operated by liquid delivered thereto in response to variations in the relative speeds of said pilot pumps, and driving means connecting said pilot motor to said adjusting element and to said displacement varying member to enable said pilot motor to adjust said main pump and said second pilot pump simultaneously.

2. A hydraulic drive according to claim 1 and including means operable in response to breakage of said material for preventing flow of liquid from said main pump to said main motor.

3. A hydraulic drive according to claim 1 and including a brake valve connected to the outlet of said main motor, and means operable in response to breakage of said material for preventing flow of liquid from said main pump to said main motor and for preventing discharge of liquid from said main motor except through said brake valve.

4. A hydraulic drive according to claim 1 and including a direction control valve connected between said main pump and said main motor, a brake valve connected to the outlet of said main motor, said control valve including a valve member shiftable to two positions in the first of which it directs liquid from said main pump to said main motor and from said motor to said pump and in the second of which it bypasses said pump and blocks communication between said pump and the outlet of said motor to thereby cause any liquid discharged by said motor to be exhausted through said brake valve, means for shifting said valve member to its first position to thereby effect operation of said main motor, and means responsive to pump pressure dropping below a predetermined value for causing said valve member to be shifted to its second position to thereby stop said main motor.

5. A hydraulic drive according to claim 1 and including means responsive to said main pump control being adjusted to a predetermined maximum pressure to effect operation of said means 45 for preventing further operation of said pilot motor.

6. A hydraulic drive according to claim 1 and including a valve for controlling said pilot motor and shiftable to two positions in one of which it permits liquid to flow through said pilot motor and in the second of which it blocks flow through said pilot motor, means including a solenoid for shifting said valve, and an electric circuit for energizing and controlling said solenoid including a limit switch operable in response to said main pump control being adjusted to require a predetermined maximum pressure to effect operation thereof.

7. A hydraulic drive according to claim 1 and 60 including a first valve for controlling said main motor, a first solenoid for adjusting said first valve to direct liquid from said main pump to said main motor, a second valve for controlling said pilot motor, a second solenoid for adjusting said second valve to permit liquid to flow through said pilot motor, and an electric circuit for controlling said solenoids and including a manual switch for effecting operation of said first solenoid, and a switch responsive to said main pump 65 creating a given pressure for keeping said first solenoid operated and for effecting operation of said second solenoid.

8. A hydraulic drive according to claim 1 and 70 including a first valve for controlling said main motor, a first solenoid for adjusting said first

valve to direct liquid from said main pump to said main motor, a second valve for controlling said pilot motor, a second solenoid for adjusting said second valve to permit liquid to flow through said pilot motor, and an electric circuit for controlling said solenoids and including a manual switch adapted when operated to cause said first solenoid to be energized, a switch responsive to said main pump creating a predetermined pressure for keeping said first solenoid energized and for causing said second solenoid to be energized, and means for deenergizing said second solenoid including a limit switch operable in response to said main pump control being adjusted to require a predetermined maximum pressure to effect operation thereof.

9. In a hydraulic drive for rotating a winding shaft on which flexible material is wound into a roll as fast as said material is delivered by a machine, the combination of a main hydraulic motor connected to said shaft to rotate the same, a main pump for supplying motive liquid to said motor to enable it to drive said shaft, said main pump having a control which in response to the pressure created by said pump rising to a given value will automatically reduce the displacement of said pump until said pump is delivering just enough liquid to maintain the pump pressure at that value and which includes an element for adjusting said control to vary the pressure required to effect operation of said control, a first pilot pump driven at a speed proportional to the linear speed of said material, a second pilot pump driven at a speed proportional to the rotary speed of said roll of material so that the speed of said second pilot pump decreases relative to the speed of said first pilot pump as said roll increases in diameter, said second pilot pump having a member rotatable to vary its displacement, fluid channels connecting said pilot pumps in series with each other and forming therewith a pilot circuit, a pilot motor having its inlet and outlet connected to opposite sides of said circuit so that it is operated in a given direction by liquid discharged by said first pilot pump in excess of the liquid that can enter said second pilot pump, and driving means connecting said pilot motor to said element and to said member to enable said pilot motor to adjust the controls of said main pump and said second pilot pump in response to said roll increasing in diameter.

10. A hydraulic drive according to claim 9 and including a direction control valve connected between said main pump and said main motor, and a brake valve connected to the outlet of said main motor, said control valve including a valve member shiftable to two positions in one of which it directs liquid from said main pump to said main motor and from said motor to said pump and in another of which it bypasses said pump and blocks communication between said pump and the outlet of said motor to thereby cause any liquid discharged by said motor to be exhausted through said brake valve.

11. A hydraulic drive according to claim 9 and including a direction control valve connected between said main pump and said main motor and also connected to said pilot motor, and a check valve connected between said control valve and the outlet of said motor, said control valve including a valve member shiftable to two positions in one of which it directs liquid from said main pump to said main motor and from said motor to said pump and in another of which it directs liquid from said main pump to said

pilot motor to cause the same to operate in the opposite direction and thereby reset the controls of said main pump and said second pilot pump.

12. A hydraulic drive according to claim 9 and including a direction control valve connected between said main pump and said main motor and also connected to said pilot motor, a brake valve connected to the outlet of said main motor, and a check valve connected between said control valve and the connection of said brake valve with the outlet of said main motor, said control valve including a valve member shiftable to three positions in one of which it directs liquid from said main pump to said main motor and from said motor to said pump, in another of which it bypasses said pump and blocks communication between said pump and the outlet of said motor to thereby cause any liquid discharged by said motor to be exhausted through said brake valve and in the third of which it directs liquid from said main pump to said pilot motor to cause the same to operate in the opposite direction and thereby reset the controls of said main pump and said second pilot pump.

13. A hydraulic drive according to claim 9 and including a reversing valve connected between one port of said pilot motor and one side of said pilot circuit, said reversing valve including a valve member shiftable to two positions in one of which it connects said one port to said one side of said pilot circuit and in the other of which it blocks said one port and connects said one side of said pilot circuit to exhaust.

14. A hydraulic drive according to claim 9 and including a direction control valve connected between said main pump and said main motor and also connected to said pilot circuit, said control valve including a valve member shiftable to two positions in one of which it directs liquid from said main pump to said main motor and from said motor to said pump and in another of which it directs liquid from said main pump to said pilot circuit, and a reversing valve connected between one port of said pilot motor and one side of said pilot circuit, said reversing valve including a valve member shiftable to two positions in one of which it connects said one port to said one side of said pilot circuit and in the other of which it connects said one port to exhaust and blocks communication between said one side of said pilot circuit and exhaust.

15. A hydraulic drive according to claim 9 and including a direction control valve connected between said main pump and said main motor and also connected to said pilot circuit, said control valve including a valve member shiftable to two positions in one of which it directs liquid from said main pump to said main motor and from said motor to said pump and in another of which it directs liquid from said main pump to said pilot circuit, and a reversing valve connected between one port of said pilot motor and one side of said pilot circuit, said reversing valve including a valve member shiftable to three positions in one of which it connects said one port to said one side of said pilot circuit, in another of which it connects said one port to exhaust and blocks communication between said one side of said pilot circuit and exhaust and in the third of which it blocks said one port and connects said one side of said pilot circuit to exhaust.

16. A hydraulic drive according to claim 9 and including a control valve having a member shiftable to either of two positions for directing liquid from said main pump to said main motor or to

said pilot motor, a reversing valve connected to said pilot motor and including a valve member shiftable to different positions to control the flow of liquid through said pilot motor, means for shifting said control valve member to a position to cause said main pump to deliver liquid to said pilot motor, and means for shifting said reversing valve member to a position to cause said liquid to operate said pilot motor in the reverse direction and thereby cause said pilot motor to reset said controls.

17. A hydraulic drive according to claim 9 and including a control valve having a member shiftable to either of two positions for directing liquid from said main pump to said main motor or to said pilot motor, a reversing valve connected to said pilot motor and including a valve member shiftable to different positions to control the flow of liquid through said pilot motor, means for shifting said control valve member to a position to cause said main pump to deliver liquid to said pilot motor, means for shifting said reversing valve member to a position to cause said liquid to operate said pilot motor in the reverse direction and thereby cause said pilot motor to reset said controls, and means responsive to said main pump control being reset to its initial position for shifting said valve members to positions to discontinue delivery of liquid from said main pump to said pilot motor and stop further operation of said pilot motor in said reverse direction.

18. A hydraulic drive according to claim 1 and including a signal for indicating when the pressure created by said main pump has reached a predetermined maximum, and means responsive to said main pump control being adjusted to said predetermined maximum pressure to effect operation of said means for effecting operation of said signal.

19. A hydraulic drive according to claim 1 and including a signal for indicating when the pres-

sure created by said main pump has reached a predetermined maximum, means responsive to said main pump control being adjusted to said predetermined maximum pressure to effect operation of said means for preventing further operation of said pilot motor and for effecting operation of said signal.

20. A hydraulic drive according to claim 9 and including a control valve for directing liquid from said main pump to said main motor or to said pilot motor, a reversing valve connected to said pilot motor to control the flow of liquid therethrough, means for adjusting said control valve to cause said main pump to deliver liquid to said pilot motor, and means for adjusting said reversing valve to cause said liquid to operate said pilot motor in the reverse direction and thereby cause said pilot motor to reset said controls, said driving means including a reduction gear driven by said pilot motor, an adjusting shaft adapted to be driven from said reduction gear and connected to said main pump control adjusting element and to said pilot pump adjusting member, a reset shaft adapted to be driven by said reduction gear and connected to said adjusting shaft, and overrunning clutches connected between said reduction gear and said shafts to permit said adjusting shaft to be driven directly from said reduction gear or to be driven by said reset shaft.
